UNITED STATES PATENT OFFICE.

CHANDLER FISHER, OF MILTON, MASSACHUSETTS.

CURTAIN-FIXTURE.

Specification of Letters Patent No. 26,980, dated January 31, 1860.

To all whom it may concern:

Be it known that I, CHANDLER FISHER, of Milton, in the county of Norfolk and State of Massachusetts, have invented an Improvement Curtain-Fixture, of which the following is a full, clear, and exact description, reference being had to the accompanying drawings, making part of this specification, in which—

10 Figure 1, is an elevation of a curtain with my improvement attached; Fig. 2, a detached view of the parts carried by the brackets to be referred to hereafter.

In the attempt to dispense with balance weights in the hanging of window curtains, a pressure has been put upon the curtain rod by a spring that bore upon one end of it and produced sufficient friction to hold the curtain in place, but it was found if the spring 15 were sufficiently strong to balance the curtain, when nearly unrolled that the latter was not easily raised or lowered and balance weights were consequently used in connection with these friction springs, whereby a 20 much smaller amount of friction was found to answer the purpose.

To remedy this necessity for balance weights, and to hold the curtain without them in any required position at the same 25 time that it may be easily raised or lowered, is the object of my present invention which consists in producing friction upon the curtain rod by means of a spring, the pressure of which is relieved when the curtain is to

be raised as will be now more fully described.

The curtain rod runs at one end in the bracket A in the ordinary manner at the opposite end, which carries the spool B, the gudgeon of the rod runs in a depression *a*, 35 in a spring *z*, attached to the bracket C. This spring is so arranged that when the curtain is left at rest the spool B, is caused by the spring *z* to bear against a metallic strip *f*, projecting from the bracket; against 40 the friction thus produced the curtain is easily lowered by drawing down the tassel D. To raise the curtain the tassel F is drawn down the spring *z* yielding sufficiently to relieve the friction between the 45 spool and the strip *f*, when the curtain is easily drawn up. Weighted tassels may thus be dispensed with, as the friction required to hold the curtain in any position offers no serious impediment to dropping the curtain, 50 while it is all relieved when it becomes necessary to raise the curtain by drawing down the tassel F.

What I claim as my invention and desire to secure by Letters Patent is—

Hanging the spool end of the curtain rod upon the curved spring *z* attached directly to the bracket C, as set forth for the purpose specified.

CHANDLER FISHER.
